US0D1107231S

(12) **United States Design Patent** (10) **Patent No.:** **US D1,107,231 S**
(45) **Date of Patent:** **** Dec. 23, 2025**

(54) **BIOPSY SYSTEM AND LATERAL ADAPTER**

(71) Applicant: **Hologic, Inc.**, Marlborough, MA (US)

(72) Inventors: **Kenneth F. DeFreitas**, Patterson, NY (US); **John Grgenti**, New Milford, CT (US); **Thomas Peter DiPersio**, Boston, MA (US); **Tri Pham**, Arlington, MA (US)

(73) Assignee: **Hologic, Inc.**, Marlborough, MA (US)

(**) Term: **15 Years**

(21) Appl. No.: **29/911,059**

(22) Filed: **Aug. 29, 2023**

(51) **LOC (15) Cl.** **24-01**

(52) **U.S. Cl.**

USPC **D24/158; D24/140**

(57) **CLAIM**

The ornamental design for a biopsy system and lateral adapter as shown and described.

DESCRIPTION

FIG. 1 is a top perspective view of a first example of a biopsy system and lateral adapter in an environment.

FIG. 2 is a top perspective view of the biopsy system and lateral adapter of FIG. 1.

FIG. 3 is a bottom perspective view of the biopsy system and lateral adapter of FIG. 1.

FIG. 4 is a front view of the biopsy system and lateral adapter of FIG. 1.

FIG. 5 is a back view of the biopsy system and lateral adapter of FIG. 1.

FIG. 6 is a right side view of the biopsy system and lateral adapter of FIG. 1.

FIG. 7 is a left side view of the biopsy system and lateral adapter of FIG. 1.

FIG. 8 is a top view of the biopsy system and lateral adapter of FIG. 1.

FIG. 9 is a bottom view of the biopsy system and lateral adapter of FIG. 1; and,

FIG. 10 is an exploded top perspective view of the biopsy system and lateral adapter of FIG. 1.

The broken lines depict an environment or portions of the biopsy system and lateral adapter that form no part of the claimed design.

1 Claim, 10 Drawing Sheets
